UNITED STATES PATENT OFFICE.

RICHARD S. MORGAN, OF EDWARDSVILLE, PENNSYLVANIA.

CHAIR FOR MINE-LOCOMOTIVES.

1,284,130.

Specification of Letters Patent.

Patented Nov. 5, 1918.

Application filed January 25, 1918. Serial No. 213,781.

To all whom it may concern:

Be it known that I, RICHARD S. MORGAN, a native-born citizen of the United States, residing at Edwardsville, in the county of 5 Luzerne and State of Pennsylvania, have invented certain new and useful Improvements in Chairs for Mine-Locomotives; and I do hereby declare the following to be a full, clear, and exact description of the invention, such as will enable others skilled in 10 the art to which it appertains to make and use the same.

This invention relates to chairs, and more particularly to a chair adapted especially 15 for combination with a mine locomotive.

It has been found that satisfactory service by operators of mine locomotives has been difficult to obtain and difficulty is found in holding this class of operators for any 20 length of time to this type of service, for the reason, that these locomotives are operated through tunnels and over very circuitous roadways, in which there are many switch overs and crossings and in which frequently 25 the curves are very sharp, with the result that the operators are violently jolted when occupying their station at the controller of the motor.

Because of the roughness of this class of 30 service, the operators are subjected to spinal strains as well also to be thrown out of their seats.

It has been proposed to provide various types of movable and yielding seats for 35 mine motor car operators, but difficulty has been encountered in the principal solution of this problem because some of the seats are not sufficiently steady, and owing to the sharp curves will rock and throw the operators.

Again the structure of same is such that they elevate the operators too high with respect to the motor and thus endanger his striking overhead or projecting obstacles 45 during the operation of the motor.

Again, chairs that have been proposed for attachment to the motors require considerable alteration of the structure and moreover are not capable of the wide range of 50 adjustment desirable for the service.

It is one of the objects of this invention to provide the combination of a mine motor car and seat or chair which will provide for the desired range of adjustment.

55 It is another object of the invention to provide a seat or chair having the desired

resilient capacity to absorb shocks and which at the same time may be readily connected to the vehicle structure with the minimum requirement of machine work or alteration 60 of the vehicle and which chair is of such construction that it will not materially elevate the operator at his station and thus minimize the danger of his encountering overhead or adjacent structures along the 65 trackway.

It is another and important object of the present invention to provide for the desired degree of resiliency to take up shocks without undue rebounding and preventing sway- 70 ing motion sidewise.

With these and other objects in view as will be readily manifest to those skilled in the art, the present invention consists of the construction, the combination, and in detail 75 arrangement of parts as set forth in the following specification which is descriptive of one form of my invention as illustrated in the accompanying drawing, wherein—

Figure 1 is a perspective view of the device as applied.

Fig. 2 is a front perspective view of the detached chair.

Fig. 3 is a perspective view looking toward one side of the chair.

Fig. 4 is a perspective view of the back of the chair.

Fig. 5 is a perspective view of the bottom of the chair.

I have shown my present invention as arranged with one type of mine motor, which has at one end a controller station 3 conveniently disposed adjacent to which is a bench or bumper structure 4.

Locomotives or motors of this class are 95 operated through tunnels or passage ways, usually of low overhead structures or formations and the operators must occupy a low position as possible at his station to avoid the overhead obstacles.

Sometimes the operator simply places or uses a cushion or seat directly on any convenient shelf or bench portion at the controller station but this is objectionable for the reason that he is subjected to serious 105 vibrations, likely to cause physical injury because of the jolting of the motor.

Therefore, I have provided a simple, substantial, practical and inexpensive chair construction and provided for the efficient 110 attachment thereof, to the motor, the attaching means providing a large capacity of ad-

justment of the chair with respect to the motor structure.

As shown, a plate 5, hereinafter referred to as the perch plate is adapted to be connected to any convenient bench or shelf portion as the bumper 4 by means of bolts or screws 6 which may be passed through apertures 7 which are arranged in a radial line from the circular head 8 at one end of the 10 plate and which is provided with an upstanding trunnion or pin 9 which may be threaded at its upper end to receive a nut 10.

The bolt or bolts 6 are adapted to be inserted in respective holes made therefor or 15 provided in the bench portion 4 of the motor.

When the bench plate 5 has been attached as desired there is then mounted on the pin 9 a chair structure shown comprising a frame 11 having a transverse member 12 20 perforated at its center to receive the pin 9 the frame also including a pair of parallel side arms or members 13 forwardly extending portions of which are pivotally connected as at 14 to the front portion or edge 25 of a seat structure 15 to the side edges of which may be attached parallel bars or reinforcing members 16 which in the present instance are hinged at 14 to the front ends of the arms 13.

30 These arms are shown as substantially straight and slightly up turned at the front ends to form the hinge 14 while at their rear ends they are provided with upturned elbows 17 having downturned or hook ends 35 18 perforated to receive the adjacent ends of springs 19 whose lower ends are hooked at 20 to the rear perforated ends of the side rods 16 which are normally held upwardly inclined as shown in Fig. 3 so that when 40 the seat 15 is occupied ample downward swing of the seat is provided when the springs 19 are elongated by the weight of the operator on the suspended seat.

The chair may or may not be provided 45 with a back though one is indicated at 22 in the present embodiment.

As clearly shown in Fig. 5 the back is upheld by a pair of L-shaped braces 21 fastened to the bottom of the seat 15 and extending up the rear of the back which latter is clearly shown in Fig. 4 as being recessed as at 22' below its top portion so as to provide within the lines of the back for movement toward and from the elbows 55 17 extending along the sides of the back and which are formed as parts of the bottom arms 13, which pass beneath the sides of the bottom of the chair.

From the above it will be seen that the 60 chair construction is of most compact arrangement so that none of the parts project materially beyond the area occupied by the seat and the back, again it will be seen that the chair can be supported in close relation 65 to the bench or shelf and thus minimize in

head room and avoid elevating the operator when he occupies the seat to any appreciable degree.

The chair seat is pivoted on an axial line which is parallel and close to its front edge 70 and is yieldingly suspended at its back to swing up and down and absorb shocks.

The chair seat is prevented from having lateral swaying motion and being rotative in a horizontal plane about its pivot pin 9, 75 enables the operator to easily climb into the seat and swing it into convenient relation to the controlling mechanism of the motor and also enables him to rapidly swing the seat to clear himself from the motor in 80 case of runaway or other events.

An important feature of the invention resides in the capacity for adjustment of the chair through a large range of positions by virtue of the perch plate 5 which may be 85 connected to the supporting bench or shelf, so as to extend with its bearing portion 8 set as shown in Fig. 2, to project the chair rearwardly from the portion to which the opposite end of the plate 5 may be connected: or as shown in Fig. 4 the bearing portion 8 of the perch plate may be set so as to project the chair in advance of the attaching portion: or again the attaching portion may be set to extend laterally of the 95 chair as is shown in Fig. 3.

These various positions of the perch plate with respect to the chair obviously will be readily determined by the construction of the motor or locomotive at the operator's 100 station.

Preferably the chair is provided with a back as shown against which the operator may lean so as to throw more of his weight on the springs and lessen the danger of being 105 thrown off when rounding curves.

The chair frame may be supported if desired on the support or brace member 5 on ball or other anti-friction bearings to provide for greater ease of its revolution about 110 its pivot pin, this being accomplished by well known devices which it is thought need not be shown in the present instance.

What I claim is:

1. The combination, with a chair of a 115 perch-plate having a perpendicular bearing for rotative connection at one end with the chair, and provided with a series of apertures to receive means for connection to a suitable support, whereby the chair may be 120 variously angularly disposed as to said support and is freely rotative on said plate.

2. A chair comprising a seat, and a frame disposed below and hinged to the front edge of the seat, and suspension means connected 125 to the rear of the seat and said frame for yieldingly suspending the seat, said frame having elbows turned upwardly at the rear of the seat and within the side lines of the seat to which said means are attached. 130

3. A chair comprising a seat, and a frame disposed below and hinged to the front edge of the seat, and suspension means connected to the rear of the seat and said frame for yieldingly suspending the seat, said frame having elbows turned upwardly at the rear and within the side lines of the seat to which said means are attached, the chair having a back which is recessed at its lower side portions to clear said means.

4. A chair comprising a seat, a substantially H-shaped frame to the front end of which the seat is pivoted at its edge, and a

bearing on which the transverse component of the frame is rotative on an axis centrally of and perpendicular to the frame.

5. A chair comprising a seat, a substantially H-shaped frame to the front end of which the seat is pivoted at its edge, and a bearing on which the transverse component of the frame is rotative on an axis centrally of and perpendicular to the frame, the frame having upturned elbows, and suspension means connecting said elbows and the seat.

In testimony whereof I affix my signature. 25
RICHARD S. MORGAN.
